CHILD'S TRAINING TOILET

Fred O. Forsman, Thousand Oaks, Calif., assignor to
Westland Plastics, Inc., Newbury Park, Calif., a cor-
poration of California

Filed Sept. 4, 1962, Ser. No. 71,548

Term of patent 14 years

(Cl. D4—5)

FIG. 1.

FIG. 2.

FIG. 3.

FIG. 4.

FIG. 5.

FIG. 1 is a top plan view of a child's training toilet showing my new design;

FIG. 2 is a side elevational view thereof, the other side of the child's training toilet being identical in appearance;

FIG. 3 is a front elevational view;

FIG. 4 is a rear elevational view; and

FIG. 5 is a perspective view taken from the rear of the child's training toilet.

I claim:

The ornamental design for a child's training toilet, as shown.
